UNITED STATES PATENT OFFICE.

THOMAS ALBERT PARKER, OF PROVIDENCE, RHODE ISLAND, ASSIGNOR TO FRANK E. WALKER AND ARTHUR C. WALKER, OF RIVER POINT, RHODE ISLAND.

ADJUSTER FOR ELECTRIC-LIGHT CORDS OR CABLES.

936,156.

Specification of Letters Patent.

Patented Oct. 5, 1909.

Application filed November 12, 1907. Serial No. 401,846.

To all whom it may concern:

Be it known that I, THOMAS ALBERT PARKER, a citizen of the United States, and resident of Providence, in the county of Providence and State of Rhode Island, have invented a certain new and useful Adjuster for Electric-Light Cords or Cables, of which the following is a specification.

The objects of my invention are to provide an electric cord or cable adjuster of simple and inexpensive construction, positive in action, readily applicable to or removable from a cord already in position without disturbing or removing the cord fixtures or fastenings, efficiently operative in any position of the adjuster, and which will afford at all times opportunity to inspect the cord or cable without removal of the adjuster. These objects I attain by the novel construction, combination and arrangement of parts hereinafter described, and shown in the accompanying drawings, in which,—

Figure 1 is a front elevation of my adjuster. Fig. 2 is a side elevation of the same. Fig. 3 is a front elevation showing the adjuster operatively applied to an electric light cord or cable.

Similar reference letters indicate like parts throughout the drawings.

A represents the body of my adjuster which is provided with a centrally located channel way A¹, extending entirely across said body and open on its front and at each end, and having its side walls disposed in converging planes, and each side wall provided with a concave channel or groove, a, meditately disposed in said wall and extending longitudinally thereof. The ends of said side walls are rounded and said groove is carried through such rounded end in order to prevent injury to the cord or its insulation. B represents a wedge-shaped binding-member arranged and adapted to be seated and operatively slidable in said channel-way A¹. The side walls of said member B are disposed in converging planes and are each provided with a meditately located longitudinally directed groove, as b, arranged and adapted, when said member is operatively seated in said channel-way, A¹, to register with the groove in the contiguous side wall of said channel way, and in conjunction therewith constitute a duct or passageway for the electric light cord or cable passed therethrough. Said member B is

provided with a meditately located oblong aperture, b¹, and a screw s, or other fastening means, passed through said aperture and into the body A thereunder, serves to hold said member B in operative position in said channel A¹, and also to limit its reciprocating movements in either direction. Said binding-member B is slid backward in said channel A¹ to afford opportunity to easily insert the cord by passing the end through one duct and back through the other in such manner that the bight of the cord will lie around the wider end of the member B, changing with easy bends from a perpendicular to a horizontal position and back to its final perpendicular position to connect with the lamp socket. (Fig. 3.)

In cases where it is desirable to apply the adjuster to a cord already installed and it is not desirable to remove or disturb the connections, the binding-member B is bodily removed from the channel A¹ on withdrawing the screw s, or other fastening means, the cord placed in the channel A¹, with its bight or loop extending beyond the wider opening of said channel, the member B inserted between the parallel runs of the cord and replaced in the channel A¹ and the screw s replaced. The cord will then be held in the juxtaposed grooves of the member B and channel A¹, as shown in Fig. 3, and strain on the cord will force the member B tightly between the side walls of said channel, and the adjuster thus secured on the cord.

To shift the position of the adjuster on the cord to shorten or lengthen the latter, or for purposes of inspection of the cord, tension applied on the cord in the direction of the bight or loop will cause the member B to slide backward out of the channel A¹ until stopped by the screw s. The cord will thus be released and may be readily inspected or the adjuster may be moved to another position on the cord, as the case may be, and the member B then forced into its clamping position. (Fig. 3.) The weight of the lamp and socket will be sufficient to hold the binding member clamped in the channel A¹.

I claim as my invention and desire to secure by Letters Patent:

An adjuster for electric light cord or cable consisting of a body member provided with a centrally located channel way ex-

extending entirely across said body and open on its front throughout its length, and having its side walls disposed in converging planes, and each said side wall provided with a meditately disposed groove extending longitudinally thereof, a wedge-shaped binding member adapted to be removably seated in said channelway for limited reciprocating movement therein, and provided 10 with a meditately located longitudinally directed oblong aperture, and with a longitudinally directed groove meditately located in each side wall and arranged and adapted to register with the groove in the contigu-

ous wall of said channelway, when said binding-member is seated therein, and to thereby constitute a duct for the cord, and means, engaging the body member through said aperture in said binding-member, arranged and adapted to hold said binding-member 15 in said channelway and permit limited reciprocating movement of said binding-member therein. 20
